2 Claims. (Cl. 25—30)

This invention relates to the molding of concrete pipes and the like including the lining of metal or other pipes with concrete or like material.

5 The specification of United States Patent No. 2,023,381 describes a method and apparatus according to which the molding and lining of pipes with concrete is effected by subjecting the concrete mixture in a semi-dry or non-liquid state simultaneously to centrifugal force and to a pronounced jolting or concussional action within a rotating mold or casing which is intermittently and abruptly projected upwardly from its normal position of rotation and returns forcibly thereto during such rotation.

10 In accordance with the abovementioned process, the mold or casing is initially rotated without the jolting action whilst the concrete mixture is being fed into the mold. Owing to its semi-dry or non-liquid consistency, the concrete is not capable of flowing or spreading longitudinally within the mold as is the case when the concrete is employed in the usual liquid or semi-liquid state in the molding of concrete pipes by the centrifugal process. For this reason, it is necessary to evenly spread or distribute the semi-dry material into annular form within the mold before subjecting it to the aforesaid combined centrifugal and jolting action. Such even spreading or leveling of the concrete is essential 15 to the production of a pipe of uniform diameter and thickness and maximum density.

20 In accordance with a preferred form of the invention, a screeding or leveling member, consisting of a straight length of tubing or circular section bar, is placed in position within the mold or casing so as to extend longitudinally therein prior to the charging of the mold with the concrete mixture. Whilst the screeding member is held in position either manually or by suitable mechanical means as hereinafter described, the material is fed into the mold which is rotated at a relatively low speed, the result being that the semi-dry material is evenly spread or distributed 25 by the screeding member into substantially annular form throughout the length of the mold. When substantially the whole of the charge of concrete has been thus introduced into the mold and initially spread therein by the screeding member, the latter is allowed to rotate while the rotation of the mold is continued at relatively low speed, whereby the leveling and pressure member exercises roller pressure simultaneously upon the entire length of the charge and ensures 30 uniform distribution of the material and par-

tially compacts same in its annular form. The screeding member is then removed and the mold or casing is subjected to combined centrifugal and jolting actions by means of a suitable apparatus provided for the purpose.

5 It has been found that by retaining the screeding member within the mold during the initial rotation and charging thereof, the subsequent combined centrifugal and jolting process causes the distributed and partially compacted semi-dry concrete mixture to be uniformly and effectively consolidated throughout the length and circumference of the mold. Furthermore, relatively small quantities of the semi-dry material may be introduced and compacted where necessary to 10 fill up any depressions or inequalities in the inner surface of the concrete pipe or lining. In this respect, it has been found hitherto that any such additional material which may be introduced for this purpose tends to remain loose 15 around the interior of the pipe and forms a rough or irregular surface.

20 Referring to the drawing which forms part of this specification—

25 Figure 1 is a longitudinally contracted side elevation of apparatus according to one embodiment of the invention.

Figure 2 is an end view of Figure 1.

30 In the drawing the numeral 2 indicates a mold provided with the usual end rings 3 which normally rests upon runner wheels 4 mounted on shafts 6 supported by bearings 7 on a framework 8. Suitable means, such as disclosed for instance in prior United States Patent No. 2,023,381, may be provided to impart pronounced jolting or concussional action to the mold while it is being rotated at high speed by the runner wheels 4.

35 In Figures 1 and 2 the screeding member is shown in the form of a straight tube 9 which extends completely through the mold and is supported so as to be spaced slightly inwards from the usual inwardly projecting flanges 3a of the mold end rings 3. Supporting means for the screeding tube may include pairs of laterally spaced end brackets 11 secured to framework 8 40 and carrying laterally extending sub-frames 12 to which upstanding arms or bearers 13 are retained. These bearers are preferably vertically adjustable and for this purpose may have a vertical slot 14 or a series of vertically spaced holes 45 to pass bolts 16 which retain them to the sub-frames 12.

50 Each bearer is provided at its upper end with a plate 17 having an open sided recess 18 of approximately semi-circular shape to accommodate 55

the screeding tube 9 so that it may rotate while being supported in operative position. With-drawable stop pins 19 or collars may be asso-ciated with the screeding member 9 to prevent 5 endwise movement thereof when in operative position.

The screeding tube is placed in operative position as in Figures 1 and 2. The semi-dry or non-flowing material is introduced into the mold 10 and the latter is rotated in the direction of the arrow in Figure 2. The recesses 18 of the plates 17 are so disposed relative to the direction of rotation of the mold that the contact of the screeding tube 9 with the material within the rotating 15 mold maintains the tube within the recess while enabling it to rotate and exercise a rolling action upon the material which facilitates distribution and initial compacting of the material. After the material has thus been distributed the screeding 20 tube may be withdrawn lengthwise from the mold and the latter then subjected to combined jolting or concussional and centrifugal actions as before referred to to complete the manufacture 25 of the pipe or lining.

Having now described my invention what I claim as new and desire to secure by Letters Patent is—

1. In apparatus for use in the manufacture or 30 lining of pipes from semi-dry or non-flowing concrete mixture, a rotary mold, means for rotating the mold to centrifugally apply the mixture to the interior thereof, a rotary leveling and pressure

member, and means for supporting same whereby it extends lengthwise from end to end within the mold in spaced relationship with the internal surface thereof so that, during rotation of the mold, the leveling and pressure member exercises 5 a rolling action upon the mixture in order to evenly spread or distribute it lengthwise and circumferentially throughout the mold into the form of a partially compacted annulus ready for 10 consolidation by combined concussion and centrifugal actions, the supporting means for said levelling and pressure member comprising up-standing arms or bearers located one at each end of the mold and provided with seatings for detachably receiving said member, said seatings 15 being provided with open-sided recesses for rotatably accommodating the end portions of the member.

2. A device of the character described, comprising a rotary mold, a supporting frame, means 20 on said frame for supporting and rotating said mold about a horizontal axis to centrifugally apply a concrete mixture to the interior thereof, a rotary pressing and leveling member extending longitudinally through said mold, a support for 25 said member positioned at each end of the mold, each support comprising a seat for rotatably accommodating the end portions of said member and provided with an open side for the introduction and removal of said member, and means for 30 adjustably securing said supports to said frame.
